UNITED STATES PATENT OFFICE.

WILLIAM DONNAN, OF BURGETTSTOWN, PENNSYLVANIA.

FLOOD-GATE.

SPECIFICATION forming part of Letters Patent No. 236,998, dated January 25, 1881.

Application filed July 28, 1880. (Model.)

To all whom it may concern:

Be it known that I, WILLIAM DONNAN, a citizen of the United States, residing at Burgettstown, in the county of Washington and 5 State of Pennsylvania, have invented a new and useful Improvement in Flood-Gates, (which has not been patented in any foreign country, nor used in this, as far as I know,) of which the following is a specification.

10 This invention relates to certain improvements in flood-gates; and it has for its object to provide an improved means for returning the gate to a normal position after it has been depressed by passing drift-wood or other débris. 15 This I attain by the apparatus and mechanism illustrated in the accompanying drawings, in which—

Figure 1 represents a perspective view of my invention; Fig. 2, a vertical sectional view 20 thereof; and Fig. 3, a detached sectional view, showing a modification of the journals and bearings of the gate.

The letter A indicates the flood-gate, which is composed of a horizontal beam, B, having 25 journals C at its ends, and provided with the pickets D, which stand vertically when the gate is in its normal position. The journal C have their bearings in the sills E, which are spiked to the bottom of the stream, at each side 30 thereof.

The letters F G indicate the springs by which the gate is returned to its normal vertical position after the passage of the drift-wood. The spring F is secured to a sill, I, confined to the 35 bottom of the stream in any suitable manner, and projects forward under the gate at one

side, being curved upward, as indicated. The spring G is attached to the upright K, secured to the beam B, and curves outwardly toward its lower end, which is adapted to bear and 40 move against the spring F as the gate works back and forth.

The various parts of the gate may be constructed of any suitable material, such as wood or metal, either in part or wholly, and the journals 45 may be secured to the side sills and have their bearings in the end of the horizontal beam, as indicated in Fig. 3 of the drawings.

The operation of my invention is as follows: The pressure of drift-wood bearing upon the 50 side of the gate swings it forward, causing the spring G to bear against the spring F, the spring G moving against the curved face of the spring F as the gate advances, the two yielding together. When the pressure is removed the 55 springs operate simultaneously as a compound spring, to return the gate to its normal vertical position, and hold it until again depressed.

Having thus fully described my invention, what I claim, and desire to secure by Letters 60 Patent, is—

The combination, with the flood-gate journaled in the sills secured to the bed of the stream, of the spring F, secured to a sill fastened to the bed of the stream, and the spring 65 G, secured to the gate, the two being adapted to operate together to return the gate to its normal position, substantially as specified.

WILLIAM DONNAN.
